UNITED STATES PATENT OFFICE.

G. RALSTON AYRES, OF PHILADELPHIA, PENNSYLVANIA, ASSIGNOR TO HIMSELF, WILLIAM MONTGOMERY AYRES, AND LOUIS H. AYRES, ALL OF SAME PLACE.

DESIGN FOR A HORSE-BLANKET.

SPECIFICATION forming part of Design No. 17,865, dated November 8, 1887.

Application filed April 26, 1887. Serial No. 230,257. Term of patent 14 years.

To all whom it may concern:

Be it known that I, G. RALSTON AYRES, a citizen of the United States, and a resident of Philadelphia, Pennsylvania, have invented a new and original Design for a Horse-Blanket, of which the following is a specification.

My design is fully shown in the accompanying drawings, in which—

Figure 1 is a side view of a horse-blanket embodying the design, and Fig. 2 an enlarged view showing more clearly the character of the stripes composing the pattern.

The blanket has the curved back-border *a*, curved neck-border *b*, front and rear borders, *d* and *f*, and bottom border, *g*, and the body of the blanket is ornamented by vertical stripes *h* and *i* and horizontal stripes *h'* and *i'*, these stripes crossing each other to form plaids inclosing blocks *w*, which are a distinct feature of the pattern, being of a color or tint contrasting with that of the groundwork of the inclosing plaid.

Each of the stripes of the plaid is composed of a series of bars, *m*, those of the stripes *h* *h'* being preferably of a distinct color or shade from those of the stripes *i* *i'*, although this feature of the design may be omitted. In all cases, however, the bars of the stripes should be so widely separated as to expose the ground-

work of the stripes for contrast with the blocks 30 inclosed thereby.

I claim—

1. The within-described design for a pattern for horse-blankets, said design consisting of stripes composed of bars separated to expose 35 the groundwork of the stripes, said stripes crossing each other to form plaids, which inclose blocks contrasting with the groundwork of the stripes, all substantially as shown and described.

2. The within described design for a horse-blanket, said design consisting of a curved back and neck border, the front, rear, and bottom borders, and the body having a pattern consisting of stripes composed of bars 45 separated to expose the groundwork of the stripes, said stripes crossing each other to form plaids, which inclose blocks contrasting with the groundwork of the stripes, all substantially as shown and described. 50

In testimony whereof I have signed my name to this specification in the presence of two subscribing witnesses.

G. RALSTON AYRES.
